COMBINED TOY AND ADVERTISING DEVICE

David C. Baker, Chicago, Ill., assignor to Fitzpatrick Bros. Inc., Chicago, Ill., a corporation of Illinois

Application June 17, 1936, Serial No. 85,787

5 Claims. (Cl. 229—8)

This invention relates to improvements in combined toy and advertising device, and one of the objects of the same is to provide improved means for stimulating the use of a commodity container 5 as a part of a sectional toy construction, and through the medium thereof to also serve as an advertising means by reason of the constant display of the container when the toy is being assembled or used.

10 A further object is to provide an improved device of this character of a collapsible or knock-down construction, the parts being adapted to be assembled to produce the toy or final product, whether there is any of the commodity in the container or not.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a side elevation of a device of this 25 character constructed in accordance with the principles of this invention and showing the parts assembled.

Figure 2 is a side elevation of the parts separated, some of the parts being in elevation and 30 some being partly in section.

Figure 3 is a top plan view of Figure 1.

Figure 4 is a view of the blank constituting one of the end members or sections, before the same is folded to shape.

Figure 5 is a view of the blank of the other end member or section before it is folded to shape.

Figure 6 is a detail perspective view of a portion of the container engaging portion of one of the end members.

40 While in the present exemplification, the invention is shown and described as constituting an animal structure, such as a lion, it is to be understood that the invention is adapted to produce any type of final product wherein the commodity container constitutes the body or torso, to the extremities of which the end members or sections are detachably connected to cooperate with the body portion. Therefore the term "animal" as employed in the specification and claims is not 45 to be considered as a term of limitation, but is to be construed broadly to include any form of final product which is composed of the parts or sections constituting this invention.

Referring more particularly to the drawings, 50 the numeral 10 designates a commodity container,

here shown in the form of a can or hollow cylindrical body provided with the usual ends, in one of which holes or apertures may be provided in the usual manner, by perforating the same, and through which openings the contents of the container may be distributed or sifted.

In the present exemplification of the invention the ends of the container 10 are shaped to form ridges 11 and the container may be of any desired size, length and configuration.

10 In Figure 5 of the drawings there is shown a blank which is shaped to form two sections 12 delineating the head 13, shoulders 14 and front legs or limbs 15 of a lion. The two sections are connected together by means of a connecting member 16, the blank being scored or partially cut along the lines 17, the two sections being separated and below the end of the connecting member 16 the blank is cut away as at 18 to form a recess, one wall being constituted by the lower edge 20 of the member 16. The lower edges 19 of the recesses 18 preferably incline upwardly from points adjacent the cut or scored portion 17 toward the center of the connecting piece 16 and terminate short of each other.

25 Similarly, the blank is cut away as at 20 along the upper end of the connecting piece 16, and which end forms one wall of the recess 20. The other wall 21 of the recess 20 is inclined downwardly from points in proximity to the cut or 30 scored line 17 towards and terminating short of each other. A portion of the blank between the end of the recess 18 and the cut or scored portion 17 may be shaped to form shoulders 22.

35 In Figure 4 there is shown a blank from which the rear section or hind portion of the animal is shaped, and this blank is shaped to form two sections 23, portions of which have the contour of the rear legs or limbs 24 of the animal and the tail 25. These sections 23 are connected together 40 by means of an intermediate member 26 and the blank is scored or cut along the lines 27, similar to the blank shown in Figure 5.

45 Each of the sections 23 is cut away as at 28 adjacent the top edge of the connecting member 26 and which edge constitutes one of the walls of the recess formed by the cut away portion while the other walls 29 of the cut away portion incline downwardly and inwardly toward but terminate short of each other.

50 Similarly, the blank is cut away as at 30 adjacent the bottom of the connecting member 26 and the lower edge of the connecting member 26 constitutes one of the walls of the recess thus formed. The other walls of the recess incline 55

upwardly as at 31 and terminate short of each other. Portions of the wall of the recess 30 may be shaped to form shoulders 32, and similarly portions of the wall 29 of the recess 28 5 may be shaped to form shoulders 33.

In use, the blank, constituting the sections 12 shown in Figure 5, are bent toward each other along the cut or scored lines 17, as shown more clearly in Figure 6, and if desired, the forward edges of the sections 12 may be brought into contact so as to hold the openings formed by the walls 20 and 19 of the recesses 21 and 18 in proper position to receive one end of the container 10, after which the forward edges of the 10 sections 12 may be separated to assume the position shown in Figure 3, thereby causing the sections 12 to be substantially parallel with each other, the inclined walls 19 and 21 engaging over the rim or flange 11 of the container. The 15 connecting member 16 extends across and in close proximity to the end of the container. With this section thus attached to the container, the legs or limbs 15 may engage and rest upon a support, and the end section will be held against accidental displacement with respect to the container by reason of the walls 19 and 21 25 engaging and resting against the side of the container beyond the rib or flange 11.

By reason of the sections 12 being separated 30 and maintained in a substantially parallel position when attached to the container and as the sections 12 are counter parts of each other, the spaced legs or limbs 15 will serve as the support for the end section as well as one end of the 35 container.

Similarly, the blank shown in Figure 4 may be folded along the scored or cut lines 27 to 40 position the sections 23 so that the recesses formed by the walls 29 and 31 and the connecting member 26 will receive the other end of the container. The walls 29 and 31 engage over the rib or flange 11 and rest against the body of the container.

The connecting member 26 will be disposed in 45 proximity to the other end of the container and the sections 23 will be held substantially parallel so that the legs or limbs 24 being separated will rest upon a support and cooperate with the legs or limbs 15 to hold the completed structure in 50 an assembled position.

It will be manifest that with this improved 55 construction a very interesting, instructive and amusing toy will result, and by reason of the formation of the separate elements which co-operate with each other, there will be produced a knock-down or collapsible structure.

When the parts are all assembled, it will be 60 manifest that the advertising matter contained on the wrapper of the container will always be visible and the device will not only serve as a toy but an advertising medium by reason of the container, that is, the container will be always exposed and the structure cannot be completed 65 without the use of the container to form the body or torso of the animal or structure.

While the preferred form of the invention has been herein shown and described, it is to be understood that various changes may be made 70 in the details of construction and in the combination and arrangement of the several parts, within the scope of the claims, without departing from the spirit of this invention.

What is claimed as new is:—

75 1. A combined toy and advertising device of

sectional construction embodying a body comprising a commodity container, separate end members of predetermined configuration, and interengaging means between the end members and the respective ends of said container for detachably securing the end members to the container, whereby said container will constitute the body or torso of the completed structure, the said interengaging means embodying spaced projections on the end members, engaging over the 10 edge of the proximate end of the container, the faces of said projections which engage over said edges, inclining upwardly from the extremity of the respective projections. 15

2. A device of the character described comprising a member comparatively long with respect to its cross sectional diameter, end members separate therefrom, one of said end members being shaped to form a head, shoulder and front leg, of an animal, the other section being shaped 20 to form the rump, rear leg and tail of the animal, and means for detachably and separately securing said sections to the respective ends of said member whereby the assembled structure will delineate a complete animal, each of said sections embodying laterally spaced portions and a connecting strip or element therebetween, which latter when the ends are secured to said member will stand adjacent and extend across the proximate 25 end of said member, said connecting strip serving as a fulcrum about which the said portions swing when the edges of the said portions are moved toward and away from each other. 30

3. A product of the character described comprising an element constituting a portion of a predetermined figure or object, in combination with a commodity container, and means for detachably securing said portion to the container, whereby the container will constitute the body or torso of the assembled structure, said portion 40 being formed from a blank cut to form complementary sections joined by an intermediate portion, along opposite edges of which portion the said sections are adapted to be folded to be substantially parallel and spaced, portions of the 45 edges of the sections adjacent the lines of fold being shaped to provide spaced laterally projecting and co-operating shoulders adapted to engage opposite portions of an adjacent end of the container providing an anchor to the container. 50

4. A blank from which an end portion of a structure delineating an animal may be formed, said blank comprising complementary sections, portions of the proximate edges of the sections being connected by a portion of the blank of substantial area, said blank being severed along the ends of said connecting portion to form spaced 55 cooperating shoulders when the blank is folded and between which shoulders the end of a body member is adapted to be positioned, said blank being also weakened along the edges of said connecting portion between said shoulders, said blank being adapted to be folded along said weakened portions, to cause the opposite edges of the blank 60 to be brought into close proximity and thereby laterally separate the shoulders on one section from the shoulders on the other section to permit ready insertion of the end of said body, the said opposite edges of the blank being separated to 65 cause the shoulders on the two sections to be moved towards each other to engage over the end of the said container to detachably secure the parts in assembled relation. 70

5. An article of the character described em- 75

bodying a body, an end element attachable to and detachable from said body, said element defining the extremity of an image of which said body constitutes a part, said end element comprising laterally spaced members hingedly connected together adjacent one edge, whereby said members at said edge will be maintained spaced, and the

opposite edges will be adapted to be moved toward and away from each other, and co-operating shoulders on each of said members at their connected edges for receiving and holding one end of said body therebetween.
